(57) **CLAIM**

The ornamental design for a wick holder, as shown and described.

DESCRIPTION

FIG. 1 is a front perspective view of a wick holder in accordance with the present invention;

FIG. 2 is a front view thereof;

FIG. 3 is a left view thereof;

FIG. 4 is a right view thereof;

FIG. 5 is a top view thereof; and

FIG. 6 is a bottom view thereof;

FIG. 7 is a front perspective view of another embodiment of a wick holder in accordance with the present invention;

FIG. 8 is a front view thereof;

FIG. 9 is a left view thereof;

FIG. 10 is a right view thereof;

FIG. 11 is a top view thereof; and,

FIG. 12 is a bottom view thereof.

The features shown in broken lines in the various Figures are for illustrating environmental structure and form no part of the claimed design.
